(57) **CLAIM**

The ornamental design for a frog toy, as shown and described.

DESCRIPTION

FIG. 1 is a first perspective view of a frog toy showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an exploded perspective view thereof, shown disassembled for completeness of illustration.

The dash dash broken lines depict portions of the frog toy that form no part of the claimed design. The long dash-short dash broken lines depict the boundaries of the claimed design, and form no part thereof.

1 Claim, 9 Drawing Sheets
